(57) **CLAIM**

The ornamental design for a vehicle mounted projector for advertising, as shown and described.

DESCRIPTION

FIG. 1 is a perspective view of a first embodiment of a vehicle mounted projector for advertising showing my new design.

FIG. 2 is a front view of FIG. 1.

FIG. 3 is a rear view of FIG. 1.

FIG. 4 is a right side view of FIG. 1.

FIG. 5 is a left side view of FIG. 1.

FIG. 6 is a top view of FIG. 1.

FIG. 7 is a bottom view of FIG. 1.

FIG. 8 is an enlarged detailed view of a portion labeled 8 shown in FIG. 1.

FIG. 9 is an alternate perspective view of the first embodiment of the vehicle mounted projector for advertising shown in an environment of use.

FIG. 10 is a perspective view of a second embodiment of a vehicle mounted projector for advertising.

FIG. 11 is a front view of FIG. 10.

FIG. 12 is a rear view of FIG. 10.

FIG. 13 is a right side view of FIG. 10.

FIG. 14 is a left side view of FIG. 10.

FIG. 15 is a top view of FIG. 10.

FIG. 16 is a bottom view of FIG. 10; and,

FIG. 17 is a perspective view of the second embodiment of the vehicle mounted projector for advertising shown in an environment of use.

The stippling shown in FIGS. 1-3, 9-14, and 17 depict a contrast in appearance. The broken lines in FIGS. 1-3, 9-14, and 17 show portions of the article that do not form part of the claimed design. The broken lines showing a car in FIGS. 9 and 17 show environment that form no part of the claimed design.

The dot-dot-dash broken lines in FIGS. 1 and 8 illustrate the border of enlarged detail views and form no part of the claimed design.

1 Claim, 13 Drawing Sheets
